SMOKE EJECTOR HANGER

Cyril Pontillo, 2301 35th St., Kenosha, Wis. 53140

Filed Apr. 9, 1973, Ser. No. 348,987

Term of patent 7 years

Int. Cl. D8—08

U.S. Cl. D8—246

Fig. 1.

Fig. 2.

FIG. 1 is a front elevational view of the smoke ejector hanger in extended position, the back being substantially similar.

FIG. 2 is a side elevational view of the device of FIG. 1.
I claim:

The ornamental design for a smoke ejector hanger, as shown and described.
